WORM PUZZLE TOY

Charles B. Root, Mechanicsville, Md., assignor to
Educational Design Associates

Filed Dec. 17, 1974, Ser. No. 533,543

Term of patent 14 years

Int. Cl. D21—01

U.S. Cl. D34—15 M

FIG. 1

FIG. 2

FIG. 3

FIG. 4

FIG. 1 is a front perspective view of a worm puzzle toy showing my new design;

FIG. 2 is a right side elevational view thereof;

FIG. 3 is a rear elevational view thereof; and

FIG. 4 is a bottom plan view thereof.

I claim:

The ornamental design for a worm puzzle toy, as shown.
